UNITED STATES PATENT OFFICE.

JAMES E. WHITMILL AND ISAAC BRUMAGE, OF DESDEMONA, TEXAS; SAID BRUMAGE
ASSIGNOR TO SAID WHITMILL.

JARRING APPLIANCE FOR BAILERS.

Application filed May 4, 1921. Serial No. 466,730.

To all whom it may concern:

Be it known that JAMES E. WHITMILL and ISAAC BRUMAGE, citizens of the United States of America, residing at Desdemona, 5 in the county of Eastland and State of Texas, have invented new and useful Improvements in Jarring Appliances for Bailers, of which the following is a specification.

10 The object of the invention is to provide simple and efficient means applicable to a bailer of the type commonly employed in connection with well drilling operations for accomplishing the loosening of the bailer, 15 when it becomes caught or jammed or otherwise locked against movement in the well, as a means of avoiding the loss of time and inconveniences incident to loosening the same with the means heretofore employed in this 20 connection and to avoid the cutting of the sand line, and to this end the invention consists essentially in connecting with the cylinder or tube of the bailer which may be of the ordinary or any preferred form, construction or dimensions, a jarring appliance 25 or attachment which can be operated by the spudding or pumping beam or through any other convenient agency without injury either to the bailer or the other parts of the 30 pump or well equipment; and further in certain details of construction and arrangement of which a preferred embodiment is shown in the accompanying drawing, wherein:

35 Figure 1 is a view of a jarring appliance embodying the invention applied in the operative position to a typical form of bailer.

40 Figures 2 and 3 are detail views respectively of the head and anvil elements attached to the jarring stem and the bailer tube or cylinder.

45 The apparatus embodies a reciprocable jarring stem 10 carrying upper and lower spaced heads 11 and 12 for alternate or selective contact with an intermediate anvil 13 secured to the tube or cylinder 14 of the bailer, the upper head preferably being formed with a suspending loop or eye 15 for attachment to a suitable operating cable or rope by which the jarring stem may be

reciprocated in a guide 16 consisting of a central bore formed in the anvil.

In the preferred embodiment of the invention the anvil element is constructed of a blank or length of bar of which the dimensions may be 3 x 3 inches cross sectionally and approximately 18 inches in length of which the terminal portions may be drawn down under a trip hammer or the like to

form arms or straps 17 for attachment by 60 rivets 18 or the equivalents thereof to the wall of the bailer tube or cylinder, the central unreduced portion of the blank being bored for example to provide an opening of

approximately one inch in diameter and then swaged out to form the guide 16 which for a jarring stem of a diameter of 1½ inches should be approximately 15/8 inches in diameter. The upper hammer head and loop, correspondingly, may be formed of a 65

similar bar of a thickness of 3 x 3 inches and a length of approximately 14 inches terminally heated and hammered to provide enlarged terminals adapted to be bent toward each other and welded together to provide a block having a bore of a diameter 70

sufficient to receive the end of the stem 10 which is preferably threaded therein as shown and is further secured by means of a key or pin 19, the intermediate portion of 75

the blank forming the loop or eye 15. The lower hammer head carried by the stem may be formed integral therewith by swaging or equivalent treatment, and in operation 80

a series of impacts by one or the other of the hammer heads upon the anvil or of alternate impacts in opposite directions of

said heads will serve to loosen the bailer under any of the circumstances tending to interfere with the free movement thereof, and without imposing upon the bailer a strain 85 which will tend to distort the same, and without involving the cutting of the sand line, or the injury of any of the other parts of the drilling or bailing mechanism. 90

95 The invention having been described, what is claimed as new and useful is:—

A jarring attachment for bailers consisting in the combination with a bailer tube or cylinder, of an anvil provided with diverg- 100

ing depending arms secured to said bailer tube or cylinder, the anvil being axially bored, a jarring stem slidably mounted in the bore of the anvil, and upper and lower spaced heads carried by the stem above and below the anvil for alternate contact with the same, the upper head being detachable

and provided with a suspending loop to which an operating cable may be attached.

In testimony whereof they affix their signatures.

JAMES E. WHITMILL
ISAAC BRUMAGE.
